UNITED STATES PATENT OFFICE.

ALPHONSO H. COBB, OF ASHEVILLE, NORTH CAROLINA.

DESIGN FOR AN EYE MEMBER FOR HOOK-AND-EYE FASTENINGS.

SPECIFICATION forming part of Design No. 31,787, dated November 7, 1899.

Application filed October 16, 1899. Serial No. 733,828. Term of patent 7 years.

To all whom it may concern:

Be it known that I, ALPHONSO H. COBB, a citizen of the United States, residing at Asheville, in the county of Buncombe and State of North Carolina, have invented and produced a new and original Design for the Eye Member of a Hook-and-Eye Garment-Fastening; and I do hereby declare the following to be a full, clear, and exact description of the invention, such as will enable others skilled in the art to which it appertains to make and use the same.

My invention consists of a design for the eye member of a hook-and-eye fastening, the said design embodying the following essential characteristics: A loop having straight substantially parallel sides lying in the same plane, connected at their forward ends by a continuous relatively short curved portion and merging at their rear ends into portions which curve suddenly inward near to, but do not touch, each other, and then curve outward, and again changing the direction of their curvature inward each describe an approximate parabola terminating at a point ad-

jacent to the starting-point of the parabola, the whole being flat and lying in substantially the same plane, as shown in the accompanying drawings.

In the accompanying drawings, which illustrate my design, Figure 1 is a plan view of the eye embodying my design, and Fig. 2 is an edge view of the same.

A represents the loop of the eye, having parallel side members A', connected by the short curved portion A² and merging at their rear ends into the inwardly-curved portions A³ and, continuing, describe the continuously-curved looped portions A⁴, terminating at A⁵.

What I claim as my invention is—

The design for the eye member of a hook-and-eye fastening, substantially as herein shown and described.

In testimony whereof I affix my signature in presence of two witnesses.

ALPHONSO H. COBB.
